UNITED STATES PATENT OFFICE

2,149,340

OSCILLATION GENERATION

Clarence W. Hansell, Port Jefferson, N. Y., assignor to Radio Corporation of America, a corporation of Delaware

Original application January 14, 1936, Serial No. 59,054. Divided and this application June 24, 1937, Serial No. 150,038

19 Claims. (Cl. 250—36)

This invention relates broadly to a new and improved thermionic tube of the cathode ray type in a new circuit for generating and multiplying alternating currents of any frequency and is a 5 division of my United States application #59,054 filed January 14, 1936.

A specific object of the parent application is to provide a new tube of the type described which is particularly adapted to relay, amplify, or frequency multiply or demodulate or modulate or convert from one frequency to another modulated or unmodulated ultra high frequency currents and to perform substantially all other services for which known thermionic tubes may be 10 used. In addition, my new tube makes possible the performance of other functions for which previously known tubes are unsuitable.

An object of the present invention is to provide new and improved oscillation generating or multiplying circuits for use with tubes of the type 20 described in the parent application when operating at ultra high frequency and lower frequencies.

In general, tubes known heretofore are limited in their application in various respects. They 25 have definite upper frequency limitations at which the inter-electrode capacity in effect provides a low reactance shunt across the impedance between the elements thereby preventing the building up of substantial potential difference 30 between the cathode and grid or anode and grid. Moreover, at ultra high frequency the grid potential reverses in a time period less than the time required for the electrons to travel from the cathode to the grid. Consequently, the tube is 35 substantially limited to frequencies, the half periods of which are greater than the time it takes for the electrons to travel from the cathode to the control grid.

Tubes of the cathode ray type have been known 40 heretofore in the art. Moreover, such tubes have been known in which steps have been taken to overcome some of the difficulties mentioned above. See, for example, Hansell United States Patent #1,938,331 issued December 5, 1933. In a particular application the electron stream has been 45 deflected laterally and thereby caused to impinge to a varying extent on one or more suitably positioned anodes. Thus, the action of the tube does not depend on the rate of flow of the electrons from the cathode to the control grid. However, in this latter tube low efficiency in operation 50 of the cathode results from the nature of the cathode and its arrangement with respect to the other electrodes. In such tubes a rather small percentage of the electron emission is used in

producing useful output from the tube. This latter defect is in general present in nearly all other cathode ray type tubes known and represents one of the main disadvantages attendant on the use of such tubes.

An object of the present invention is to provide a new tube of the cathode ray type which is less limited as to frequency by the rate of flow of the electron stream from the cathode to the control grid.

Another object of the present invention is to provide a new and improved tube of the cathode ray type as described in the preceding paragraph in which the electrodes are arranged in a novel manner to obtain the utmost use of the electron stream. In this manner, high efficiency and high electron current are obtained.

The novel features of my tube and of various circuits in which said tube may be utilized have been pointed out with particularity in the claims 20 appended to this specification.

The nature of my novel tube and the mode of operation of the same and of the circuits connected therewith will be better understood by the following detailed description and therefrom 25 when read in connection with the drawings through which like reference characters indicate like parts and in which

Figures 1, 2, 4, and 5 show, for purposes of illustration, various modifications of my novel 30 tube structure;

Figure 3 illustrates by curves the operation of the tubes of my invention;

Figure 6 illustrates a circuit arrangement wherein the novel tube of my invention is connected 35 in a novel circuit and coupled to a source of oscillations to produce oscillations of increased frequency;

Figures 7 to 14 illustrate the use of my novel tube in novel circuits arranged to produce sustained oscillations of considerable amplitude and substantially constant frequency.

In Figures 7 to 14 inclusive, regeneration is produced between the anode circuit and the accelerating electrode circuit.

In Figure 12, the frequency of the oscillations produced is controlled by means of a resonant, low power factor line;

Figure 15 illustrates diagrammatically the essential elements of a novel transmitter circuit including oscillation generating and modulating circuits incorporating the tubes of my invention; while

Figure 16 shows diagrammatically a novel circuit arrangement wherein a thermionic tube of 55

the present invention controls the amplification of a radio frequency amplifier in a novel fashion in accordance with the intensity of signals characteristic of the signals impressed on the amplifier.

Referring to the drawings and in particular to Figure 1 thereof, 2 is a low voltage high current cathode axially located with respect to an accelerating and control electrode 4 which as shown 10 has an inner periphery relatively close to one end of the cathode 2 and an outer periphery which is relatively widely spaced from the cathode 2. The intermediate portions of the accelerating and control electrode 4 recede from the 15 cathode as shown from the inner periphery to the outer periphery thereof. The cathode 2 is supplied as shown with heavy heating current through heavy leads L coaxially with the cathode which may be connected as shown to a source of 20 cathode heating current. The anode 6 is located coaxially with respect to the heating leads of the cathode and is separated from the electron emitting portion of the cathode by a disk-shaped portion 7 arranged as shown. The anode may be 25 maintained at the desired direct current potential by connecting the same as shown to the positive terminal of a source of potential.

The arrangement as shown causes electrons leaving different points along the cathode to be 30 accelerated at different rates by the control electrode 4 and to acquire different velocities in their travel from the cathode toward the anode. Those leaving the end of the cathode near A acquire a higher velocity than those leaving the cathode 35 near the point B. The velocity which may be imparted to the electrons may decrease progressively from the point A to the point B and may decrease at various rates as desired by properly shaping the accelerating electrode 4.

40 Due to the large cathode current, which should be derived from a constant direct current source, a magnetic field exists around the cathode and its end connections. This magnetic field deflects the electrons drawn out from the cathode toward the anode, if the cathode current is in the correct direction. Those electrons having high 45 velocity travel a relatively long path in the magnetic field, while those having a low velocity, travel a relatively short path. As a result when the tube is arranged in accordance with my invention, all electrons leaving the cathode at one instant strike the cathode stem 7 or the anode 6 at substantially the same later instant. Moreover, in the arrangements shown all electrons leaving from different points along the cathode 50 between points A and B tend to strike the cathode stem at the right of B, or the anode, at the same instant. In other words, in my novel tube there is a strong focussing of the electron stream on a 55 ring enclosing the cathode lead, which may be selected at will. The location of the ring on which the electrons are focussed is a function of the intensity of the electron stream, the potential of the anode, and of the energizing and shaping of the electrodes, and in particular of the accelerating control electrode 4.

The electron flow has been indicated diagrammatically by the shaded areas in Figure 1. These areas in particular indicate the outside limits of the electron path in their passage from cathode to anode or from cathode to the cathode stem. The shaded areas 10 which come to sharp points on the anode are intended to show a cross section of the volume occupied by moving electrons when the anode current is a maximum. This condi-

tion is attained principally by applying a predetermined potential between 2 and 4. The overlapping shaded areas 12 which come to sharp points on the shield 7 on the cathode stem are intended to show a cross-section of the volume 5 occupied by moving electrons when the anode current is zero. This condition is attained when the potential on 4 is made less positive relative to 2.

By varying the potential between the accelerating control electrode 4 and the cathode 2, the position at which the electrons strike the anode or return to the cathode stem or to the shield 7 on the cathode stem may be varied. Therefore, the current flow to the anode may be controlled by 15 simply varying the potential between the control electrode and cathode or by varying the anode potential or both. It may also be controlled by varying the cathode current in any manner to vary the magnetic field but in the present application I prefer to use variation in electric forces instead.

By adding annular shields 7 and 14 to the cathode stem as shown in Figure 1 on each side of the anode, the electrons may be shielded from the electric field of the charged anode during most of their flying time and variations in anode potential will have little effect upon the anode current. This results in a high anode impedance similar to that of shield grid tubes of 30 the type already known in the art and gives a high amplification constant without requiring flow of current to the control electrode during peaks of anode current.

Obviously the electron current may also be 35 made to fall upon the shield 14 by making the potential of 4 sufficiently positive with respect to 2. By making adjustments for varying the electron current between shield 14 and anode 6 the alternating current polarity of the tube output is 40 reversed to what it would be when the electron current is varied between shield 7 and the anode.

45 My novel cathode ray tube may take many forms. For example, the tube may be arranged as indicated in Figure 2. In Figure 2, one end of the cathode terminates in a conductive disk 9 as shown. The disk 9 serves not only to supply heating current to the cathode but also as a shield between two chambers within the tube envelope. One chamber includes the input electrodes which 50 are to be connected to the input circuits, while the other chamber includes the output electrodes which are to be connected to the output circuits. This, of course, increases the stability of operation of the tube particularly when it is operated 55 at high frequencies at which shielding between output and input circuits is desirable. Moreover, in Figure 2 the anode 6 has a U-shaped cross section as shown. This reduces or eliminates flow of current from anode 6 to electrode 9 due to 60 secondary emission from the anode when, in operation the anode potential may be negative with respect to electrode 9 during portions of the operating time.

65 It should be noted in connection with the arrangements shown in Figures 1 and 2 that by adjusting the control electrode potential above or below that required to give maximum anode current we may reverse the polarity of the alternating current output with respect to the alternating current input potential and current. This 70 feature is not possessed by ordinary tubes, though need for it is often met with in keying and signalling circuits. As an example, we may convert from single circuit to pushpull circuit amplifica- 75

tion, detection, etc., by feeding the inputs of two of the tubes in parallel while connecting their outputs in pushpull, provided we have the action reversed in the two tubes.

The principles of my new type vacuum tube may very well be applied to providing more efficient cathodes for all sorts of cathode ray tubes, including those in which the brightness of the spot is modulated in addition to the spot being moved over a fluorescent screen (kinescope tubes). They may also be applied to television transmitting tubes such as Dr. Zworykin's "Iconoscope".

To obtain some idea as to the correct dimensions to use in a tube suitable for receiving purposes I will assume that the control electrode and anode are each maintained at a positive direct current potential of about 135 volts with respect to the cathode. The effective diameter of the control electrode and twice the maximum distance electrons are to travel out from the axis of the cathode will be assumed to be .3" or 300 mils.

Then, for an approximate equation take Hull's Equation I on page 915 of Transactions A. I. E. E., vol. XLII, 1933, which is

$$E = 0.0188 I^2 (\log_{10} D/d)^2$$

where

E = voltage.

I = cathode current in amperes.

D = diameter of anode (in this case effective diameter of accelerating and control electrode)

d = diameter of cathode

Substituting in this equation we get:

$$135 = 0.0188 I^2 (\log_{10} 0.3/d)^2$$

or better yet use Hull's Equation 2, which assumes a cathode temperature of 2500° K., then:

$$40 \quad E = 0.000716 d^3 \text{ mils} (\log_{10} D/d)^2$$

or

$$E = 0.000716 d^3 (\log_{10} 300/d)^2$$

The values of E for various assumed values of d become

d	E
Mils	Volts
3	0.0774
30	19.35
60	75.5
90	143
150	218

The values have been plotted in Figure 3 and indicate that a cathode diameter of about 86 mils would be required for a control electrode having an effective diameter of about 0.3 inch.

If we assume $D=0.6$ inch then the control electrode voltage for various cathode diameters will be

d	E
Mils	Volts
30	32.8
40	63.4
50	104
60	155
70	216
90	354

In this case a cathode diameter of 57 mils would be about right.

It is noted that plain tungsten filaments, of the sizes required for operation of 135 volts on

the control electrode, will require filament currents of the same order of magnitude as we use in water cooled tubes.

If a tube is arranged in accordance with my invention and includes a 40 mil filament having an active length of .5 inch in combination with a control electrode of 1 inch effective diameter, we would obtain in the ideal case a peak anode current of .5 ampere and in doing so we would use a direct current control electrode potential of 90 volts. With 90 volts on the anode we might obtain a maximum alternating current output of about 2.5 watts. By raising the anode potential we should obtain about 25 watts at 900 volts and 250 watts at 9000 volts. The filament power required would be about 100 watts. The power and voltage gain obtainable will be very high in my new tube.

Since very heavy cathode current is objectionable in receiving tubes other means in addition to those shown in Figure 2 for focussing the electron stream on the anode or target besides the magnetic field is desirable. Such a focussing and electron timing scheme has been shown in Figure 4. In this figure the tube comprises a control electrode 4 and indirectly heated cathode 2 having a radially enlarged shielding portion 5 as shown. The cathode 2 and control electrode 4 are separated from the anode by a shield and accelerating electrode 9. Annular openings are provided in the shield 9 to permit the electron stream, when properly focussed, to reach the anode 6. The anode 6 is, as in Figure 2, U shaped in cross section. This shaping of the anode minimizes the effect of secondary emission by reducing the possibility of potential gradients where secondary emission is produced by primary electron impacts upon the anode surface and so preventing the secondary emission produced from reaching the other electrodes. The diaphragm electrode 9 is preferably charged to a more positive potential than the accelerating and control electrode 4. Preferably the diaphragm 9 is brought outside the glass envelope of the tube as shown to provide a continuation of the metal partition between the two shielded compartments in the tube. The continuation of the diaphragm 9 may also serve as the mounting for the tube upon the metallic shield 18, which effectively isolates the input circuits from energy feed back from the output circuit.

In the operation of the tube electrons leaving the filament are first acted on chiefly by an electric field due to the control electrode 4. The force is greatest on electrons leaving the cathode from points farthest from the anode. This is due to the shield on the end of the cathode and the size, shape, spacing and potentials of the other electrodes. After the electrons leave the cathode they come more and more under the influence of the electric field produced by the diaphragm electrode potential and this bends the electron paths in approximately the same way as the magnetic field in the tubes of Figs. 1 and 2. I so arrange, shape and energize the electrodes that all electrons leaving the cathode arrive at the diaphragm electrode 9 at nearly the same radial distance from the axis of the tube. Moreover, the electrons leaving the cathode at the same instant arrive at the diaphragm at nearly the same later instant and consequently are concentrated on the anode at the same instant.

The areas 16, enclosed by the dotted lines, in Figure 4 represent the electron paths for the condition of maximum anode current. For other

control electrode potentials than that assumed in Fig. 4 the electrons would miss the openings in the shield 9, which also acts as an accelerating electrode, partially or altogether and so reduce the anode current to any desired value between maximum and minimum.

By varying some of the electrode potentials the distance from the axis of the tube at which the electrons arrive at the diaphragm electrode 9 may be varied. Consequently the electrons may be made to strike either the diaphragm 9 or the openings in it accordingly to the electrode potentials. If they strike the openings they will, of course, land on the anode and produce an anode current. Consequently, we may control the anode current by varying the control electrode or cathode potential with respect to the diaphragm, or we may vary both. I prefer to vary only the control electrode potential in most cases.

In Figure 4 I have shown openings in the diaphragm 9 of considerable axial length so that there will be little potential gradient inside these openings. This reduces the forces acting on secondary emission electrons and reduces the secondary emission from the diaphragm which can arrive at the anode.

Of course, my novel tube is applicable to all classes of signalling including transmitting as well as receiving. Where large powers are to be handled I contemplate cooling one or more of the electrodes of the tube. For example, as shown in Fig. 5 the anode electrode 6 of the tube may be cooled by a circulating fluid. The cathode 1 is somewhat similar to the cathode 2 of Figs. 1 and 2. Here, however, the cathode terminates in a radially expanded portion 5 which is continued axially as shown at 5' to form a shield for the cathode 2 and for the accelerating electrode 4. This axial portion 5' may also serve as one of the leads L' for applying the heating current to the cathode. The radial portion of the shield has openings therein as shown through which the electrons may reach the anode 6. The magnetic field from the cathode current deflects the electrons as in the tubes of Figs. 1 and 2. The dotted lines in the upper half of Fig. 5 show the condition of maximum anode current while those in the lower half show a condition of zero anode current. Another condition of zero anode current can be obtained by increasing the positive control electrode potential to make the electrons strike outside the openings in 5.

The tube of Fig. 5 may, of course, normally be used with a fluid cooled output circuit inductance or coil of copper tubing through which water may be circulated to the anode as disclosed in Moser, United States Patent #1,857,029 dated May 3, 1932. See also Hallborg's United States Patent #1,963,131 dated June 19, 1934. Although I have shown an anode made of metallic tubing with a cylindrical cross section area it will be understood that the tube may have other shapes. If the tubing has a disk shape or U shaped cross section such that the electrodes strike the anode in a depressed area as they do in Figures 2 and 4 secondary emission will be reduced and the effect of that which takes place will be reduced.

Since to obtain high efficiency in any of the tubes in the foregoing figures as an oscillator or class C amplifier, we must drive the anode potential down almost to zero when anode current flows, we must provide for the condition where the anode potential is below the diaphragm potential. This requires suppressing the effect of secondary emission from the anode. The anode

in my tube is so shaped as to give very low potential gradient where the initial electrons strike. This reduces the secondary emission current which can flow back from anode to diaphragm. Preferably a carbonized anode, or anode of material selected to minimize secondary emission, is used.

The tubes of the present invention may be utilized for any purpose for which any known types of vacuum tubes can be used and, in addition will perform functions for which other known types of tubes are unsuitable.

When it is desired to relay or amplify alternating current potentials or direct current impulses of any frequency, with circuits similar to those shown in Figure 1, the said impulses may be applied to the leads marked "input", connected to the primary winding of a transformer 30, the secondary winding of which is coupled as shown between the control and accelerating electrode 4 and the cathode 2. The last named connection may, if desired, be by way of a bypassing condenser C. The secondary winding of the transformer may be tuned to the frequency of the oscillations or impulses to be relayed if desired by a variable condenser 31 connected as shown. The relayed and amplified oscillations impressed on the input electrodes are repeated in the tube in the manner described hereinbefore and caused to appear on the anode electrode 30 from which they may be set up in an output circuit including a primary winding connected as shown between the anode 6 and the cathode 2 by way of a second by-passing condenser C'. This primary winding of transformer 32 may be tuned by a variable condenser 33 connected as shown. The oscillations appearing in this tuned circuit may be impressed on the secondary winding coupled thereto and transferred from said winding to any utilization circuit by way of the leads marked "output".

The anode electrode may be connected as shown to a positive point on a source of direct current potential, the negative terminal of which is connected to ground and to the cathode. The control electrode and accelerating electrode 4 may be maintained at the desired potential with respect to the cathode by connecting electrode 4 to a separate source of potential or to the desired point on the first named source. The sources of potential may be a battery or a filter network connected with a rectifier.

In the description of the novel circuits in which my novel tube operates, which follows, the tube has been shown somewhat schematically. The tube of each of the circuits may be the tube shown in Figures 2, 4, or 5.

In Figure 6 I have shown diagrammatically a frequency multiplying system wherein the thermionic tube of the present invention having its accelerating electrode and cathode 2 connected to a tuned circuit 40 coupled to a source of high frequency oscillations O. The anode 6 of this tube is connected to tuned circuit 40' which is in turn coupled to an output circuit. A variable capacity VC is connected as shown between the anode electrode 6 and accelerating electrode 4 to produce the necessary feedback. The anode circuit 40' may be tuned to a harmonic of the oscillations 20. The oscillations of increased frequency may be supplied from the circuit 40' to any load circuit, as for example an antenna system TA.

Here, as in the prior case, the oscillations to be amplified or demodulated may be shunted

around the energizing source by way of by-passing condensers C, C' and C'', connected as shown between the low potential ends of the input and output circuits and ground and from ground to the cathode of the tube.

When it is desired to generate oscillations, an arrangement as shown in Figure 7 may be utilized. Here, the filament may be heated from a source of heating current through a transformer 10 connected to the filament by a circuit 8 as shown. A tuned oscillatory circuit 45 may be connected as shown between the controlling and accelerating electrode 4 and the electrical center of the filament heating circuit by way of ground and 15 condenser C. The anode electrode 6 may be connected to an inductance 47 variably coupled to the inductance in the tuned circuit 45. When proper potentials are applied to the electrodes 4, 9 and 6, sustained oscillations will be produced 20 in the tube and circuits 45, 47 and said oscillations may be supplied to any utilization circuit such as an aerial by way of a coupling condenser 48, connected as shown to the anode 6. High frequency oscillations appearing in the circuit 45 25 and in inductance 47 and on the shielding electrode 9 may be by-passed around the potential sources by way of by-passing condensers C, C' and C'', connected as shown from the low potential ends of the anode accelerating electrode and 30 shield electrode circuits to ground.

The oscillator shown in Figure 8 is similar in many respects to the oscillator shown in Figure 7. In the oscillator of Figure 9, however, a tuned anode circuit 49 is utilized and is variably coupled 35 to an inductance connected with the controlling and accelerating electrode 4.

In the oscillator of Figure 9, a tuned oscillatory circuit 45 is connected between the accelerating electrode 4 and the cathode 2 and a tuned oscillatory circuit 49 is connected between the anode and the cathode and coupled to the first named circuit, thus inductive feedback coupling is provided and oscillations may be produced with either polarity of feedback coupling provided 45 suitable power supply potentials are applied to the tube.

Figure 10 shows an oscillation generator with a tuned anode circuit 49, tuned accelerating electrode circuit 45, and either capacitive or conductive feedback coupling, depending upon the size of the capacity 52 in the feedback circuit. Since the tube may be adjusted for either polarity of output with respect to input, by adjusting the bias on 4, and the tuned circuits 45, 49 may be 55 either exactly tuned or detuned in either direction from the frequency of oscillation, I may use either polarity of feedback. A switch S in the feedback circuit is shown for reversing the feedback polarity.

Figure 11 shows an oscillation generator with a tuned anode circuit 49 and tuned circuit 45 connected with the accelerating electrode 4, having feedback through a piezo-electric quartz crystal PC for stabilizing the frequency. Undesired capacity feedback between the electrodes of the crystal holder may be neutralized by means of a neutralizing condenser NC connected as shown between the high potential terminal of the crystal PC and a point on the tuned circuit 45. A shield 54 may be interposed between the anode and control electrode circuits, as shown, for the purpose of reducing the undesired feedback between these circuits.

Since the tube will operate to generate oscillations with either polarity of output relative to

input, I may reverse the connections from the crystal and neutralizing condenser where they tap on the inductance in the accelerating electrode oscillation circuit 45.

The frequency of the oscillations generated by my novel tube and circuits may be stabilized as shown in Figure 12, by a low power factor resonant circuit or transmission line 60, points on which may be connected by way of movable taps 61 and 62 to the tuned resonant circuit 45 connected with the accelerating electrode 4 and the tuned resonant circuit 49 connected with the anode electrode 6. In this case, the polarity of the feedback may be reversed if desired by means of the reversing switch S. The resonant transmission line may be as disclosed in my United States application #692,092 filed October 4, 1933, Patent 2,095,980, granted October 19, 1937. When the proper charging potentials are applied to the electrodes in the tube, oscillations are developed 20 in the tubes and circuits and energy is transferred from the tuned resonant circuit 49 to the low power factor circuit or line 60 and from the line to the tuned resonant circuit 45 to reinforce said oscillations and stabilize the frequency 25 thereof. In a modification, the connections from the oscillatory circuits 46 and 49 may be made to the same end of the resonant circuit or transmission line 60. In this case, the line may be made substantially one-quarter wave length long 30 or any multiple of one-quarter wave length long, and then feedback of sufficient amplitude and correct phase will only be obtained at the resonant frequency of the line. A resonant low power factor line for feedback and stabilizing purposes 35 in an oscillatory generator has been disclosed in United States application #692,092 filed October 4, 1933, Patent 2,095,980, granted October 19, 1937.

In some cases, it may be desired to produce and modulate oscillations by means of a single 40 tube. In this case, a circuit arrangement as shown in Figure 13 may be utilized. Here, the controlling and accelerating electrode 4 and screening electrode 9 are connected in oscillation producing circuits including the tuned oscillatory circuit 60. The oscillations produced 45 are modulated in the anode circuit and supplied from the anode circuit by way of the transformer 62 to any utilization circuit. In order to prevent reaction of the anode and output circuit on the oscillation producing circuits, a neutralizing condenser 68 may be connected as shown between the anode 6 and a point on the tuned circuit 60.

The modification shown in Figure 14 is similar to the oscillation generator of Figure 13, except 55 that a piezo-electric quartz crystal PC has been included in the circuit connected with 4. In parallel with the crystal PC is an impedance 64, which supplies direct current potential to the electrode 4. The crystal on proper adjustment 60 of potentials and circuits will stabilize the frequency of the oscillations produced in the self-oscillation circuit including the electrodes 2, 4, 9, the piezo-electric crystal PC and the tuned circuit 60. Here, as in the modification of Figure 13, the modulating potentials may be applied by way of a transformer 50 to the anode electrode 6 and the device may be neutralized by a condenser 68. The modulating potentials may be supplied to any circuit by way of coupling condensers 69 and 70.

In Figure 15, I have tubes of the present invention connected in a novel transmitting circuit. This transmitting circuit comprises an oscillation generator 90 in which the accelerating 75

electrode 4 is regeneratively coupled by way of a piezo-electric crystal PC to the tuned tank circuit 92 connected with anode 6 in such a manner that sustained oscillations of a frequency determined by PC are produced when the electrodes are energized. The crystal has another electrode connected to the shielding and accelerating electrode 8. The shielding between the anode electrode and circuit and the accelerating electrode 10 and circuit afforded by 9 may be supplemented by a screen S arranged as shown. The electrode 4 may be charged with a positive potential by way of a resistance 93. The oscillations appearing in 92 are transferred by way of a lead 94 to the accelerating electrode 4' of an amplifier stage 96 wherein they are amplified and appear in the tuned tank circuit 98 connected with the anode 8' from which they are supplied in push-pull relation to the accelerating electrodes 4" of a pair 20 of power amplifiers or modulators in an amplifying and modulating stage 100. The modulating potentials are supplied from a transformer 95 to the accelerating electrode 101 of a tube in an amplifier stage 102 and from the anode 103 of said amplifier stage to the accelerating electrode 104 of a tube in the modulator stage 106. This tube has its anode 107 connected to the anodes of the push-pull power stage 100 to accomplish therein anode modulation of the carrier waves. Note 30 here that the use of my novel tube wherein the accelerating electrode may be charged positive permits this electrode to be connected directly to the anode of the preceding tube as in stages 90, 96 and 102, 106. The many advantages flowing 35 from this simplifying of the exciting circuits which permits the anode and accelerating electrodes of adjacent cascaded stages to derive their energy from the same source will be apparent to one skilled in the art.

40 The stage 96 may operate as an amplifier and as a frequency multiplier. In the latter case, the circuit 98 is tuned at a harmonic of the frequency of the oscillations produced in 90. The modulated oscillations may be impressed on any utilization circuit from the tuned circuit 110 connected with the anodes 9" of the tubes in the stage 100.

When it is desired to receive transmitted signals of any character, I may utilize a receiving system as illustrated in Figure 16. This system may comprise a receiving aerial 110 coupled to an amplifier 112 which is in turn coupled to an amplifier 114. The output of the amplifier 114 may be connected to demodulate on detector 116 and the output of said detector may be coupled to a low frequency amplifier 118, the output of which may be coupled to any utilization circuit, as for example telephones. In order to control the output of the receiver and maintain the same 55 relatively constant, irrespective of swings in the amplitude of the received wave, I couple the amplifier 114 to a tuned circuit 120 coupled between the accelerating electrode 4 and cathode of a thermionic tube. The anode electrode of the 60 thermionic tube is connected as shown by way of a source 122 and a resistance 124 to the cathode of the tube. The resistance 124 may be connected as shown by way of an automatic volume control line AVC to the accelerating electrode 65 and cathode of one or more thermionic tubes in the amplifier 112, to thereby control the gain of 70 said amplifier tube in accordance with the potential drop in the resistance 124. The potential drop in the resistance 124 is in turn a function of 75 the amplitude of the received signal. When the

signal amplitude increases above normal, the gain of the amplifier 114 is reduced and the opposite effect is produced by a decrease in the received signal amplitude. In practice the location of the source 122 may be changed or other anode circuits may be used.

I claim:

1. In a system for producing high frequency oscillations, a thermionic tube having an elongated electron emission element which when heated produces diffused emission in a direction away from the axis of the tube, means for heating said emission element, an accelerating and control electrode located adjacent one end of said emission element, an additional electrode mounted adjacent the other end of said emission element, an alternating current circuit connected between said first named accelerating and control electrode and said emission element, and an alternating current circuit connected between said additional electrode and said emission element, each of said last named circuits including means for coupling one to the other.

2. A system as recited in claim 1 in which the alternating current circuit connected with the additional electrode of said tube is tuned.

3. A system as recited in claim 1 wherein both of said alternating current circuits are tuned.

4. A system as recited in claim 1 wherein both of said alternating current circuits are tuned and wherein the coupling between said circuits includes means for reversing the sense of coupling.

5. A system as recited in claim 1 wherein said circuits and coupling includes frequency stabilizing means.

6. In a system for producing high frequency oscillations, a thermionic tube having an elongated electron emission element which when heated produces diffused emission in a direction away from the axis of the tube, means for heating said emission element, an accelerating and control electrode located adjacent one end of said emission element, an additional electrode mounted adjacent the other end of said emission element, an alternating current circuit connected between said first named accelerating and control electrode and said emission element, a second alternating current circuit connected between said additional electrode and said emission element and means for coupling one of said

circuits to the other of said circuits, said means comprising a low power factor resonant line connected between said circuits whereby the frequency of the oscillations produced is stabilized.

7. In a system for producing high frequency oscillations, a thermionic tube having an elongated electron emission element which when heated produces diffused emission in a direction away from the axis of the tube, means for heating said emission element, an accelerating and control electrode located adjacent one end of said emission element, an alternating current circuit connected between said accelerating and control circuit and said emission element, an anode mounted adjacent the other end of said emission element, said anode being connected to an output circuit and an additional shielding and accelerating electrode mounted between said anode and said first named electrode, and means for coupling said output circuit to said alternating current circuit.

8. In a system for producing high frequency oscillations, a thermionic tube having an elongated electron emission element which when heated produces diffused emission in a direction

away from the axis of the tube, means for heating said emission element, a control and accelerating electrode located adjacent one end of said emission element, an anode electrode mounted adjacent the other end of said emission element, an accelerating and shielding electrode mounted intermediate said anode and said emission element, an alternating current circuit connected between said first named accelerating electrode and said emission element, means for maintaining said shielding electrode positive relative to said emission element, and an alternating current circuit connected between said anode and said emission element, each of said last named circuits including means for coupling one to the other.

9. A system as recited in claim 8 in which an alternating current circuit is also connected between said shielding electrode and said emission electrode.

10. In a system for producing high frequency oscillations; a thermionic tube having an elongated electron emission element which when heated produces diffused emission in a direction away from the axis of the tube, means for heating said emission element, an accelerating and control electrode located adjacent one end of said emission element, an anode electrode mounted adjacent the other end of said emission element, and an accelerating and shielding electrode mounted intermediate said anode and said emission element, an alternating current circuit connected between said first named accelerating electrode and said emission element, means for maintaining said shielding electrode positive relative to said emission element, an alternating current circuit connected between said anode and said emission element, said last mentioned means including a low power factor resonant line connected to each of said circuits whereby the frequency of oscillations produced is stabilized.

11. A system as recited in claim 8 wherein both of said alternating current circuits are tuned and wherein the coupling between said circuits includes a frequency stabilizing means.

12. In a system for producing high frequency oscillations, a thermionic tube having an elongated electron emission element which when heated produces diffused emission in a direction away from the axis of the tube, means for heating said emission element, a control and accelerating electrode located adjacent one end of said emission element, an anode electrode mounted adjacent the other end of said emission element, and an accelerating and shielding electrode mounted intermediate said anode and said emission element, a tuned circuit connected between said first named accelerating electrode and said emission element, said tuned circuit including a tapped inductance, means for maintaining said shielding electrode positive relative to said emission element, a second tuned circuit connected between said anode and said emission element and means for coupling said tuned circuits one to the other including a reactance connected to said second tuned circuit, a switch connected to said reactance and selectively connectible to the taps on the inductance in said first tuned circuit whereby the coupling sense between said tuned circuits may be reversed.

13. A system as recited in claim 8 wherein both of said alternating current circuits are tuned and wherein said coupling is inductive and variable.

14. In a system for producing high frequency oscillations, a thermionic tube having an elongated electron emission element which when heated produces diffused emission in a direction away from the axis of the tube, means for heating said emission element, an accelerating and control electrode located adjacent one end of said emission element, an additional electrode mounted adjacent the other end of said emission element, an alternating current circuit connected between said first named accelerating and control electrode and said emission element, a second alternating current circuit connected between said additional electrode and said emission element and means for coupling one of said circuits to the other of said circuits, said means including a piezo electric crystal connected therebetween.

15. In a system for producing high frequency oscillations, a thermionic tube having an elongated electron emission element which when heated produces diffused emission in a direction away from the axis of the tube, means for heating said emission element, an accelerating and control electrode located adjacent one end of said emission element, an additional electrode mounted adjacent the other end of said emission element, an alternating current circuit connected between said first named accelerating and control electrode and said emission element, a second alternating current circuit connected between said additional electrode and said emission element and means for coupling one of said circuits to the other of said circuits, said means including a piezo electric crystal connected therebetween and neutralizing means connected between a point on said first mentioned alternating current circuit and the end of said second circuit remote from said additional electrode.

16. In a system for producing high frequency oscillations, a thermionic tube having an elongated electron emission element which when heated produces diffused emission in a direction away from the axis of the tube, means for heating said emission element, an accelerating and control electrode located adjacent one end of said emission element, an additional electrode mounted adjacent the other end of said emission element, a tuned circuit connected between said first named accelerating and control electrode and said emission element, said tuned circuit including an inductance having a plurality of taps connected thereto, a second tuned circuit connected between said additional electrode and said emission element and means for coupling said tuned circuits comprising a low power factor resonant line connected to said second circuit and selectively connectible to said taps on the inductance in said first named circuit whereby the coupling sense between said circuits may be reversed.

17. In a system for producing high frequency oscillations, a thermionic tube having an elongated electron emission element which when heated produces diffused emission in a direction away from the axis of the tube, means for heating said emission element, an accelerating and control electrode located adjacent one end of said emission element, an anode electrode mounted adjacent the other end of said emission element, and an accelerating and shielding electrode mounted intermediate said anode and said emission element, an alternating current circuit connected between said first named accelerating electrode and said emission element, means for

- 5 maintaining said shielding electrode positive relative to said emission element, an alternating current circuit connected between said anode and said emission element, each of said last 5 named circuits including means for coupling one to the other and a shield surrounding said tube in the plane of said accelerating and shielding electrode.
- 10 18. In a system for producing high frequency oscillations, a thermionic tube having an elongated electron emission element which when heated produces diffused emission in a direction away from the axis of the tube, means for heating said emission element, an accelerating and 15 control electrode located adjacent the end of said emission element, an anode electrode mounted adjacent the other end of said emission element, and an accelerating and shielding electrode mounted intermediate said anode and said emission element, an alternating current circuit connected between said first named accelerating electrode and said emission element, means for maintaining said shielding electrode positive relative to said emission element, an alternating 20 current circuit connected between said anode and said emission element, each of said last named circuits including means for coupling one to the other and a shield surrounding said tube in the plane of said accelerating and shielding 25 electrode, said means including a piezo electric

crystal connected between said circuits whereby the frequency of the oscillations produced is stabilized.

19. In a system for producing high frequency oscillations, a thermionic tube having an elongated electron emission element which when heated produces diffused emission in a direction away from the axis of the tube, means for heating said emission element, a control and accelerating electrode located adjacent one end of said emission element, an anode electrode mounted adjacent the other end of said emission element and an accelerating and shielding electrode mounted intermediate said anode and said emission element, an alternating current circuit connected between said first named accelerating electrode and said emission element, said circuit including a tapped inductance, means for maintaining said shielding electrode positive relative to said emission element, an alternating current circuit connected between said anode and said emission element and means for coupling said alternating current circuits together, said means including a low power factor resonant line connected to said second circuit and selectively connectible to the taps on the inductance in said first mentioned circuit whereby the coupling sense between said circuits may be reversed. 20 25
